BAG PACKER WEIGHING ASSEMBLY

Edwin J. Douglas, Whittier, Calif., assignor, by mesne assignments, to Cherry-Burrell Corporation, Cedar Rapids, Iowa, a corporation of Delaware

Filed Mar. 30, 1960, Ser. No. 18,648

1 Claim. (Cl. 177—120)

This invention relates to weighing assemblies for bag packers and the like. In particular, the invention is concerned with improving the accuracy and speed with which bags may be packed with material by a high speed bag packer.

Devices for high speed bag packing, utilizable with a variety of materials, are well-known. An example of such a bag packer is illustrated in my United States Patent No. 2,827,256, issued March 18, 1958, and assigned to H. L. Stoker Company, Claremont, California. The bag packer therein described consists essentially of a U-trough having a hopper attached thereto and holding a screw conveyor. A drive assembly is provided to rotate the screw conveyor. Material is fed into the U-trough through the hopper and conveyed by the screw conveyor out of the U-trough and into a bag connected to a spout at the end of the conveyor. A weight sensing device is provided to weigh the material packed in the bag from the U-trough.

A bag packer of my aforesaid patent is capable of packing bags with material at a very high rate while maintaining accuracy in the weight of material filled in each bag and from bag to bag. That bag packer utilizes a two-speed drive arrangement by means of which the material to be packed is fed into the bag at a high rate of speed until the bag is substantially filled, whereupon the rate of packing is very greatly reduced so as to complete the filling of the bag with a high degree of accuracy with respect to the weight of material filled. The weight sensing device senses two weight end points which occur during the filling of the bag. Control means are actuated at each of the two end points successively to reduce the rate of the screw conveyor rotation and then reverse the screw conveyor rotation, so as to provide a sharp cutoff in filling. By providing such a sharp cutoff, a reproducible accuracy in filling from bag to bag is accomplished.

However, the bag packer described in the aforesaid patent has the comparative disadvantage of not maintaining a high constant flow rate of material throughout the packing cycle. While providing speeds of packing and accuracy of measurement equal or superior to conventional bag packers, such speed and accuracy is achieved by utilizing a variable rate of flow of material. Therefore, an even greater rate of packing is possible if the high initial rate of packing can be maintained throughout the packing cycle.

Bag packers have conventionally utilized as the primary weighing element a scale beam connected so as to constitute a lever of the first class. In other words, conventional bag packer weighing assemblies, consisting essentially of a weighing platform adapted to hold a bag, a scale beam, and means for counterbalancing the weight of the material in the bag, have had the weighing platform connected at one end of the scale beam and the counterbalancing means connected at the other end of the beam. A pivot point between the two connections acts as a fulcrum so that the scale beam constitutes a lever of the first class. The movement of the scale beam, as the material packed into the bag and the force exerted by the counterbalancing means equalize each other, whereupon the scale beam assumes a horizontal position, has been utilized to actuate microswitches and relays to terminate packing of the material by the bag packer screw conveyor. In such conventional bag packers, both the load applied to the scale beam by the weighing platform and the force

2

applied to the scale beam by the counterbalancing means are applied in a downward direction.

According to the present invention, a weighing assembly is constructed so that the scale beam constitutes a lever of the second class. The weighing platform applies the load in a downward direction, as in conventional bag packers, but the counterbalancing means applies a force in an upward direction, whereas previous bag packers applied such a force in a downward direction. The movement of the scale beam upon the substantial counterbalancing of the weighing platform load by the counterbalancing means is utilized to terminate the packing of the bag.

It is preferred to include a weight beam connected so as to constitute a first class lever with a weight attached at one end thereof as the counterbalancing means. The fulcrum of the weight beam lever is positioned so that the weight beam amplifies the movement of the scale beam upon the substantial counterbalancing of the weighing platform load. The amplified motion of the weight beam is then used to terminate the packing of the bag. For example, a capacity-sensitive electrical circuit having a variable capacitor, the capacitance of which is varied by movement of the weight beam, may be utilized to terminate the packing of the bag at a predetermined value of capacity of the variable capacitor.

The invention may be more readily understood by referring to the drawings in which:

FIGURE 1 is a block diagram of a bag packer weighing and packing control assembly according to the invention;

FIGURE 2 is an elevation, partially in section, of a bag packer according to the invention;

FIGURE 3 is a fragmentary elevation of the bag packer of FIG. 2 illustrating the construction of the weighing assembly;

FIGURE 4 is a partial section taken along lines 4—4 of FIG. 2 illustrating the means by which the weighing platform is supported from the weighing assembly frame; and

FIGURE 5 is a partial view of a scale beam arm of the device illustrating the construction of the fulcrum pivot point thereof.

Referring now to FIG. 1, a screw conveyor 11 is contained in a trough (not shown) into which material 12, which is to be packed, is fed. The rotation of the screw conveyor by a screw conveyor drive motor 13 causes the screw conveyor to transport the material contained in the trough through and out of a spout 14 and into a bag 15.

A weighing platform 16 is adapted to support the bag 15 while the bag is being packed with material. The weighing platform 16 is connected to a bag weighing device 17 which drives a variable capacitor 18. The variable capacitor 18 is connected to a screw conveyor drive controller circuit 19.

A power supply 20 is connected to a bag packer start switch 21. The bag packer start switch is operable to apply electrical power to the contacts of a forward drive relay 22 and a reverse drive relay 23. Completion of an electrical circuit through one of these drive relays 22, 23 to the screw conveyor drive motor 13 will cause the screw conveyor drive motor to rotate the screw conveyor

11 in the appropriate direction. The completion of electrical circuits through the drive relays 22 and 23 is controlled by the screw conveyor drive controller 19. A reverse drive timer 24 is connected in series with the screw conveyor drive controller 19 and the reverse drive relay 23 to control the duration of the reverse drive of the screw conveyor 11.

The operation of the screw conveyor drive controller 19 is controlled by the capacitance of the variable capacitor 18. The screw conveyor drive controller 19 is normally operable to complete an electrical circuit through the forward drive relay 22 so that the conveyor screw

11 is rotated to transport material through and out of the spout 14. However, at a predetermined value of capacity of the variable capacitor 18, the screw conveyor drive controller 19 breaks the electrical circuit through the forward drive relay 22 and actuates the reverse drive timer 24. The reverse drive timer 24 functions to complete an electrical circuit through the reverse drive relay 23 for a preselected duration of time, thereby causing the screw conveyor 11 to be driven in the reverse direction for this time duration. The screw conveyor 11 is driven in the reverse direction to provide a sharp cutoff in filling, as is described in my aforesaid patent.

A satisfactory reverse drive timer is an Agastat Model 9050 Timer. A satisfactory screw conveyor drive controller is a Robertshaw-Fulton Model 201 Capacity-sensitive Relay. The Robertshaw-Fulton Model 201 relay is preferably connected to the variable capacitor by coaxial cable.

FIGURE 2 shows a bag packer constructed according to the invention. A weighing platform 30 is connected to a weighing assembly frame 31 by lower straps 32 and upper straps 32', which are more clearly shown in FIGS. 3 and 4. The weighing platform 30 includes a spout 34 connected integrally therewith. A screw conveyor (not shown) extends through a U-trough 35 which has a hopper 36 connected thereto.

The construction of the spout 34, U-trough 35 and hopper 36 is illustrated in FIGS. 3 and 4 of my copending Application Serial No. 805,397, filed April 10, 1959, and assigned to the H. L. Stoker Company, Claremont, California, using a flexible seal. A drive motor 37 drives the conveyor screw through a removable screw assembly 38 and a V-belt 39. The preferable construction of the removable screw assembly 38 is illustrated in my Application Serial No. 831,201, filed August 3, 1959, and assigned to the H. L. Stoker Company, Claremont, California.

A scale beam 40 is pivoted at one end from the frame 31, as is shown more clearly in FIG. 3. At the opposite end a weight beam connecting member 42 connects the scale beam to one end of a weight beam 43. The weight beam 43 has a poise weight 44 and a hanger weight 45 attached thereto. A pivot 46 attached to the assembly frame 31 supports the weight beam 43 and acts as the fulcrum for the weight beam. Thus, the weight beam constitutes a first class lever. A first capacitor plate 47 is attached to the end of the weight beam 43 adjacent the weights 44 and 45. A second capacitor plate 48 is connected to the assembly frame 31 by an adjustable height standoff insulator 49 to provide electrical isolation between the capacitor plate 48 and the frame. Movement of the weight beam 43 in a vertical direction will thus vary the capacitance of the variable capacitor 18 (FIG. 1) formed by the first and second capacitor plates 47 and 48.

The weighing platform 30 is connected to the scale beam 40 by a weighing platform connecting member 50. A counter poise weight 51 on the weight beam 43 and a counterpoise 52 on the scale beam provide a means for adjusting the "zero" position of the assembly. An "over/under" indicator 53 is attached to the end of the scale beam adjacent the capacitor plate 47 to provide visual indication of the correctness of the weight of material filled.

FIGURE 3 illustrates the detail of the construction of the weighing assembly of the bag packer. A bag seat 60 of the weighing platform 30 is connected to the spout 34 by a channel-shaped connecting member 61. The scale beam 40 is pivoted from the frame 31 by a pivot 63. The construction of the pivot 63 is preferably a 60° male pivot knife mating with a 120° female pivot slot. The female pivot slot is preferably formed by milling a 120° slot in the scale beam 40. Tungsten carbide inserts are fixed in the slot in alternate order along the slot faces with an epoxy resin adhesive. A sharp V notch in the

slot, in which the male pivot knife rides, is thereby achieved. It has been found that the conventional milled slot is unsatisfactory for this pivot. The weighing platform connecting member 50 is connected to the scale beam 40 by a pivot 64, and to the weighing platform 30 by a pivot 65.

The weight beam connecting member 42 is connected to the scale beam 40 by a pivot 66. The construction of the pivots 64-66 is more fully described in my aforesaid U.S. Patent No. 2,827,256. These pivots have the advantage of a construction such that the material being packed cannot infiltrate into the pivotal surfaces to impede free pivoting action. The weight beam connecting member 42 should be vertical. The scale beam 40 is therefore preferably constructed so that the position of the pivot 66 may be shifted to insure that the weight beam connecting member 42 is vertical.

FIGURE 4 illustrates in more detail the straps 32 which connect the weighing platform 30 to the assembly frame 31. The straps 32 are preferably constructed of clock spring steel 1095 rolled to width so as to provide resilient support for the weighing platform and reproducible recovery characteristics. The straps 32 are preferably .032 inches thick. A weighing platform support bracket 67 connects the straps 32 to the weighing platform 30.

By positioning the pivot 64 adjacent the pivot 63 and utilizing a long arm for the scale beam 40, and by attaching the weight beam connecting member 42 adjacent the weight beam pivot 46, a high amplification of the vertical movement of the weighing platform 30 is obtained in the weight beam 43. Such a high amplification has two principal advantages. First, a relatively small weighing platform movement produces a comparatively great movement of the first capacitor plate 46, thereby providing a great variation in the capacitance of the variable capacitor. Second, the hanger weight 45 is comparatively light with respect to the weight of material in the bag being counterbalanced. Conventional systems require a comparatively heavy weight for such counterbalancing. Precise measurement of the weight of material in the bag requires that the weight beam movement have no appreciable time delay with respect to the actual weight of material in the bag. Movement of the weight beam also moves the hanger weight. A heavier hanger weight, in addition to providing as a counterbalancing force its own weight, adds as an additional counterbalancing force its inertia, which tends to prevent the movement of the weight beam. By the present invention, an extremely light hanger weight is utilized and the inertia thereby introduced is negligible, so that no appreciable time delay due to the temporary counterbalancing force of the balance weight inertia is introduced.

FIGURE 5 illustrates in detail the construction of the female pivot slot of the pivot 63 described with respect to FIG. 3. A 120° slot is cut in the pivot block 70 so as to present a first face 71 and a second face 72, each at an angle of 60° to the block face 73. Ground tungsten carbide chips 74, ground preferably to parallelism, are placed in alternate order on faces 71 and 72 of the block 70. The chips 74 are held in place preferably by a material such as an epoxy resin.

A practical construction of the scale beam provides for the load pivot point, that is, the point at which the pivot 64 is positioned, to be placed two inches from the pivot point of the fulcrum pivot 63 and the force pivot point, that is, the point at which the load beam connecting member 42 is connected to the scale beam 40, be thirty inches from the pivot point of the fulcrum pivot 63. The load beam connecting member is attached to the load beam three and one-quarter inches from the pivot point of the load beam support 46. The hanger weight 45 is attached to the load beam twenty-one and five-eighths inches from the pivot point of the load beam support 46. The first capacitor plate 47 is connected to the load beam twenty-

six inches from the load beam support 46 pivot point. A hanger weight of one pound is then used to counter-balance one hundred pounds of material packed into the bag.

Using these dimensions, a downward vertical movement of .0025 inch by the weighing platform where the system is in balance results in the first capacitor plate 47 moving a sufficient amount to actuate the circuit to give a cutoff. This high amplification in movement of over one hundred times, insures a rapid change in capacity of the variable capacitor. The rapid change in capacity provides a reproducible actuation point for the reverse drive of the screw conveyor. By using the reverse drive timer, the reverse rotation of the screw conveyor is also accurately controlled so that reproducible results are obtained in packing bags. The exact instant for terminating packing may be adjusted by raising or lowering the stand-off insulator 49. Using the above described system and dimensions, bags can be packed with one hundred pounds of material with a reproducible accuracy of within one ounce. In order to maintain such reproducible accuracy, it is essential that the strength of the components in the device be sufficient to preclude deformations due to loading other than movement of the weighing lever assembly and support straps.

I claim:

A weighing assembly for a bag packer comprising a weighing platform including a bag seat and a filling spout adapted to support a bag being filled with material, a weighing assembly frame, at least one resilient horizontal connecting member attached to the weighing platform and the weighing assembly frame so as to support the weighing platform and simultaneously permit the vertical movement of the bag support assembly in response to the weight of the material contained in the bag, said one connecting member comprising a pair of resilient suspension straps that are connected to the weighing assembly frame and extend from opposite sides of the frame in substantially parallel directions in a substantially horizontal plane, a weighing platform support bracket connected between the ends of said suspension straps, means for con-

necting said weighing platform to said support bracket, a first pivotal support means that is fixed relative to the weighing assembly frame, a first substantially horizontal beam pivotally supported at one end by said first pivotal support means, a second substantially horizontal beam, a vertical beam connecting member connecting one end of the second beam to the end of the first beam not pivotally supported, means for attaching a weight to the end of the second beam not connected to the first beam by the vertical connecting member, a second pivotal support means that is fixed relative to weighing assembly frame, said second pivotal support means supporting the second beam at a point between the weight and the connecting member, a vertical weighing platform connecting member connecting the weighing platform to the first beam at a point intermediate between the first pivotal support means and the vertical beam connecting member, and means associated with the second beam to terminate the filling of the bag in response to a predetermined amount of movement of the second beam.
